UNITED STATES PATENT OFFICE

WILLIAM R. MANN, OF SHARON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

ELECTRIC SWITCH AND CONTACT STRUCTURE THEREFOR

Application filed November 30, 1928. Serial No. 322,686.

This invention relates to electric switches and particularly to switches wherein laminated brush members are carried by and electrically connected with the lower ends of spaced stationary switch members and has for an object the provision of means to improve the contact therebetween.

It is the practice to provide the current conducting studs with screw-threaded end portions on which to support the laminated brush members between a pair of spaced clamping nuts. The individual lamina, and especially the intermediate laminae of the brush consequently make little or no direct contact with the stud, and the current flowing through the switch passes transversely through the brush, or across the superposed laminae thereof, to the outer laminae. Thus the current path through the intermediate laminae includes one or more of the high resistance contact junctions between plates, each of which offers considerable resistance to the passage of current. As a result considerable heat is generated in the brush which in turn causes oxidization of the contacting surfaces of the laminae and further increases the heating of the brush. Frequently, the temper of the brush becomes destroyed due to the heat generated therein and the brush is unable to maintain the necessary contact pressure, resulting in arcing at the contact faces which soon renders the switch inoperative.

An object of this invention is to provide a contact structure especially of the inverted brush type wherein each lamina of the brush provides a separate low resistance path between the movable switch member and its supporting stud.

A further object of the invention is to provide an inverted brush structure in which each lamina of the brush has a section thereof in pressure engagement with its supporting and conducting stud.

A still further object is to provide a brush structure in which each lamina of the brush has an edgewise contact area in engagement with its supporting stud which area is at least as great as the cooperating contact face of the lamina.

A still further object is to provide an in-

verted brush having increased resilience, thus to prevent "stubbing" of the cooperating contact face.

A further object is generally to improve the construction of electric switches and contact structures therefor.

Fig. 1 is a side elevation, partly in section, of the current conducting members of an electric switch embodying the present invention.

Fig. 2 is a sectional elevation showing in detail an inverted brush and its supporting stud constructed in accordance with the invention.

For purposes of illustration the invention is embodied in a down break electric switch, only that part of the switch being shown which is necessary to disclose the invention.

As herein shown, the stationary switch members include the conducting studs 10 and 12, which are disposed within and supported by the spaced insulating bushings 14 and 16. Laminated brush members 18 and 20 are fixed detachably to the lower extended ends of said studs 10 and 12 in a manner hereinafter described, which studs thus constitute holders for the brush members. Said brush members 18 and 20 are of the inverted, non-reactive, type and comprise a plurality of superposed laminae of resilient conducting material, each having a horizontal supporting section 22 and an angularly related depending toe section 24. Said toe sections are directed downwardly and inwardly toward each other and terminate in substantially horizontal contact faces 26 which are disposed in a position to be bridged by the movable switch member.

Said movable switch member includes the vertically reciprocable switch operating rod 28 of wood or other suitable insulating material having a metal ferrule 30 secured fixedly to its lower end to which the movable contact bridging member 32 is pivotally secured by means of a pin 34. Outstanding flanges 36 on said ferrule 30 overlie the upper surfaces of said bridging member 32 and are slightly spaced therefrom whereby to limit the pivotal movement of said bridging member on said pin 34. Said bridging member 32 is provided with flat contact faces 38 at either end which are adapted to engage the hori-

zontal contact faces 26 of the stationary brush members 18 and 20 when the movable switch member is moved upwardly into the switch closed position shown in Fig. 1.

According to the present invention the 5 conducting studs 10 and 12 are provided with downwardly tapered brush supporting portions 40 and reduced screw threaded end portions 42 therebeneath. Said studs are further provided with screw threads 44 above said tapered portions 40, and nuts 46 are threaded thereon in position to bear against the lower ends of bushings 14 and 16, whereby to prevent upward movement of the studs in the bushings. The brush supporting actions 22 of the brush members 18 and 20 are provided with correspondingly tapered holes to receive the tapered portions 40 of said studs 10 and 12 closely therewithin, whereby to bring a sectional area of each lamina of the brush into contact with the stud.

Clamping nuts 47 are screw threaded on said lower reduced end portions 42 whereby to clamp each lamina of the brush members forcibly against the tapered portions 40 of said studs. When clamped in position on the tapered portions 40 of the studs the brush members are arranged to be situated below and slightly spaced from the nuts 46 and are also arranged to extend somewhat below the shoulder 48 formed by the reduced end portion 42 and the tapered end portion of said studs. The pressure of the clamping nuts 47 against the brush is thus directed entirely against the tapered portions 40 of the stud, whereby to bring the annular tapered section of each lamina of the brush member into forcible engagement with the stud. Lock nuts 50 may be disposed beneath said clamping nuts 46.

By the provision of the invention each lamina of the brush members is brought into direct pressure-engaging relation with its supporting stud whereby each provides a separate current conducting path between its supporting stud and the movable bridging member 32, irrespective of the other laminae of the brush, thus eliminating from the circuit the resistance of the surface contact junctions between adjacent laminae of the brushes. Each lamina has a cross sectional area thereof in intimate contact with the tapered portion 40 of the stud, which area is at least as great as the area of its contact face 26 and provides an individual current conducting path independent of the adjacent laminae. Since a low resistance path is provided, little or no current will pass laterally through the brush from one to the other of the laminae and the heating of the brush member is largely eliminated. This is a distinct advantage over the prior art wherein the laminated brush member was received loosely on a straight screw threaded portion of the stud

and, at most, only a casual connection existed between the intermediate laminae and the tops of the screw threads on the stud.

To assist in conducting the current from the inner to the outer laminae, which were the only ones having good electrical connection with the stud, it was formerly necessary to solder the horizontal supporting sections of the laminae together. This resulted in a brush so stiff that "studding" occurred at the cooperating contact face. This trouble is entirely obviated by the present invention. Since each lamina of the brush provides an individual current path to the stud, it is unnecessary to connect the horizontal supporting sections 22 electrically, thus greatly increasing the flexibility of the brush without increasing the lateral spacing of the stationary switch members. A jacket 52 may be provided about the horizontal supporting section 22 to form a convenient unitary brush structure, but with the tapered brush and stud construction set forth the several laminae are free to flex slightly, thus greatly improving the operation of the switch and particularly the contact members thereof.

The construction may be modified in many ways without departing from the scope of the invention.

I claim:

1. In an electric switch, the combination of a brush holder, a laminated brush member having a passage therethrough which is so formed that the laminae have tapered faces in said passage, and means connected with said holder located in said passage and having a surface corresponding with and in independent engagement with the tapered faces of the laminae.

2. In an electric switch, the combination of a brush holder, a laminated brush member having a tapered passage therethrough, and means connected with said brush holder having a tapered section conformed with and received in said tapered passage and making independent contact with each brush lamina.

3. In an electric switch the combination of a current conducting stud having a tapered lower end portion, a laminated brush member carried by said stud, each lamina having a correspondingly tapered passage therethrough, the side walls of which abut against the tapered portion of said stud, and pressure applying means arranged to urge the tapered side walls of said laminae into current conducting engagement with said stud.

4. In an electric switch, the combination of a current conducting stud having a tapered end portion, a laminated brush member having a correspondingly tapered passage therethrough to receive the tapered portion of said stud, and pressure applying means directed axially of said stud arranged to urge each of the laminae of said brush firmly against the tapered portion of said stud, whereby to pro-

vide a separate current conducting path from said stud through each lamina of said brush.

5. In an electric switch, the combination of a current conducting stud having a tapered lower end portion, a laminated brush member having a correspondingly tapered passage through the laminae thereof and adapted to be received on the tapered portion of said stud, and means to clamp said brush member against the taper of said stud arranged to maintain edgewise contact between each lamina thereof and the tapered portion of said stud.

10 In testimony whereof, I have signed my name to this specification.
